CLAIM

The ornamental design for a bracket with grooved track wheel, as shown and described.

DESCRIPTION

FIG. 1 is a front, perspective view of a bracket with grooved track wheel in accordance with the principles of the present design;

FIG. 2 is a rear, perspective view of the bracket with grooved track wheel of FIG. 1;

FIG. 3 is a side view of the bracket with grooved track wheel of FIG. 1;

FIG. 4 is a top view of the bracket with grooved track wheel of FIG. 1; and,

FIG. 5 is a bottom view of the bracket with grooved track wheel of FIG. 1.

In the drawings, the broken lines depict environmental subject matter only and form no part of the claimed design.
